UNITED STATES PATENT OFFICE

PERRY W. SULLIVAN, OF SOUTH BEND, INDIANA, ASSIGNOR TO THE STUDEBAKER CORPORATION, OF SOUTH BEND, INDIANA, A CORPORATION OF NEW JERSEY

DOOR GLASS GUIDE

Application filed June 24, 1931. Serial No. 546,515.

This invention relates to a door glass guide and has for its principal object to provide a guiding and bracing means for the top of a door glass used in a door having a sloping door post.

5 A further object is to provide a device of this character that is neat and inconspicuous and which will not detract from the appearance of the vehicle on which it is used.

10 A further object is to provide a device of this character which is simple and rugged in construction and which is economical to manufacture and easy to install, and will not readily get out of order in service.

15 A still further object is to provide a door glass guiding and bracing means that is solid and rigid in construction and effectively prevents the top of the door glass from vibrating or rattling.

20 Having thus set forth the principal objects and advantages of my invention, the same will now be described in connection with the accompanying drawings to enable others skilled in the art to make and use the same.

25 It is to be understood, however, that the preferred form of the invention as illustrated and the modified forms as illustrated in connection therewith comprise, merely a few concrete examples of the many ways in which 30 this inventive idea may be applied. The description and illustration in the drawings are to be taken as illustrative only, and the invention is to be limited solely by the scope of the subjoined claims.

35 Referring to the drawings in which like reference numbers apply to similar parts throughout:

Figure 1 is a fragmentary side elevation of an automobile showing a door of the form to 40 which this invention is particularly adaptable.

Figure 2 is a fragmentary elevation of a vehicle door showing a portion of the sliding glass thereof and my invention applied 45 thereto.

Figure 3 is a view similar to Figure 2, on an enlarged scale, some of the parts being broken away to more clearly illustrate the construction of the device.

50 Figure 4 is a fragmentary view of the top

portion of the sliding glass for a vehicle door showing my invention applied thereto and illustrating on an enlarged scale the detailed structure of the device.

Figure 5 is a view similar to Figure 3 showing a modified form of the invention.

Figure 6 is a detailed view of the construction illustrated in Figure 5.

Figure 7 is an elevational view showing in detail the construction of a further modified 60 form of the invention.

Figure 8 is a fragmentary view showing a modification of a detail of the device illustrated in Figures 3, 4 and 6.

Figure 9 is an end elevation of the detail 65 shown in side elevation in Figure 8.

Figure 10 is an end elevation of a detail of the device illustrated in Figures 3, 4 and 6.

Referring to Figure 1, the numeral 10 generally indicates the vehicle door having a 70 window 11, and a sliding glass closure 12 for said window, receivable in the lower portion 13 of said door. In this illustration, the door has a vertical door post 14 at one side thereof and a sloped door post 15 at the opposite side thereof. The vertical door post 14 has a 75 vertical guide groove 16 formed therein, as shown in Figure 3, and the glass 12 has a straight edge 17 vertically slidable in the groove 16. The sloping door post 15 has a 80 guide groove 18 therein, as shown in Figure 3, parallel to the edges of the door post. The glass 12 has a sloping edge 19 corresponding to the slope of the door post 15 and it will be noted from an inspection of Figures 1 and 85 2, that when the glass is completely raised, the sloping edge 19 fits into the groove 18 in the sloping door post 15, as shown in Figure 1. However, as the glass is lowered, the straight edge 17 runs in the vertical groove 90 16, but the sloping edge 19 tends to pull away from the sloping groove 18, leaving a gap between the edge of the glass and the adjacent door post. This leaves a considerable area of the glass unsupported, and when so 95 unsupported, the glass has a tendency to vibrate and rattle and may be easily broken if the door is heavily jarred or slammed.

To overcome these disadvantages, I have provided a means for bracing the top edge 100

of the glass as it pulls away from the sloping groove and also to guide the glass back into the groove when the window is closed. This means comprises the following structure: A tubular member 20 having an external groove in one side thereof is mounted on the top edge of the glass and preferably securely cemented thereto. Within the tubular member 20 there is telescopically inserted a rod 21 having a bent-over and rounded end 22 slidable in the guiding groove 18. The member 21 is shorter than the tubular member 20, and in another portion of the tubular member, I place a compression spring 24 which has an adjustable abutment 25 at one end and at the other end bears against the inner end of the member 21. In the remaining portion of the tubular member 20, I provide an adjusting screw 27 which is screw threaded through the abutment 25, and at the opposite end has a reduced portion extending through a bearing member 28. This adjusting member has a squared end 29 projecting out of the tubular member 20 and accessible when the glass closure 12 is lowered so that the adjusting member may be turned to adjust the tension on the spring 24. In the abutment 25 is a small set screw 30 which projects through the tubular member 20 and which may be adjusted to lock the adjusting member 27 in adjusted position.

From this description, it will be apparent that as the glass 12 is raised and lowered in the door, the member 21 will be thrust outwardly by the spring 24 so that the end 22 will slide in the guiding groove 18 and thereby support and steady the top edge of the glass 12.

The members 20 and 21 are neatly designed and smoothly finished, and preferably are chromium plated so that the addition of the device will in no way detract from the pleasing appearance of the vehicle.

So far the description has been restricted to a door having only one sloping door post. However, it is quite possible that it may be desirable to slope both of the door posts inwardly at the top thereof. I have shown such a construction in Figure 5, and in Figure 6 I have shown a guiding and bracing means suitable for use in connection with this type of door, and in Figure 7 I have shown a modified form of such a device.

Referring to Figure 6, it will be observed that I have provided the top edge of the glass with a tubular member 20 as described above. However, in this case I have telescopically inserted rod members 35 and 36 in each opposite end of the tubular member, and between the opposed inner ends of the rod members I have inserted a compression spring 37 to thrust the rod members outwardly and maintain the ends 38 and 39 thereof in the guiding grooves in the respective door posts.

In the modified form shown in Figure 7,

I have provided the door glass with tubular members 20 and 40 on both the top and bottom edges thereof respectively, the tubular members being provided with external grooves cemented to the glass as explained above. For the guide members, I have provided a pair of rod members generally indicated at 41 and 42, each having an intermediate portion 43 the length of the sloping edge of the glass between the top and bottom tubular members, and having bent-over ends 44 bent at such an angle to the intermediate portion that the ends are telescopically received in the top and bottom tubular members and the intermediate portion lies along and parallel to the sloping edge of the glass. Between the inner opposed ends of the guiding members within the top and bottom tubular members, I have provided compression springs 46 and 47 to thrust the guide members outwardly and maintain the intermediate portions 43 thereof in the guiding grooves in the sloped door posts 15 and 23.

In the modification shown in Figures 8 and 9, I have provided a slide member 22' joined to the rod 21 intermediate its ends instead of at the upper end thereof as shown in Figures 6 and 7.

Having now described my invention and the purpose thereof, I claim:

1. In a door having a window in the upper portion thereof, a sliding glass closure for said window receivable in the lower portion of said door, a sloping door post on at least one side of said door having a guide groove therein, a sloping edge on said glass corresponding to the sloping of said post, a guide member mounted on the top of said glass having a part slidably received in said groove, an adjustable abutment mounted on said glass opposite said guide member, and a compression spring between said abutment and said guide member.

2. In a door having a window in the upper portion thereof, a sliding glass closure for said window receivable in the lower portion of said door, a sloping door post on at least one side of said door having a guide groove therein, a sloping edge on said glass corresponding to the slope of said post, a guide member mounted on the top of said glass having a vertically elongated part lying within a cut-away portion of said glass and slidably received in said groove, an adjustable abutment mounted on said glass opposite said guide member, and a compression spring between said abutment and said guide member.

3. In a door having a window in the upper portion thereof, a sliding glass closure for said window receivable in the lower portion of said door, a sloping door post on at least one side of said door having a guide groove therein, a sloping edge on said glass corresponding to the slope of said post, a guide member mounted on the top of said glass hav-

ing a vertically elongated part slidably received in said groove, an adjustable abutment mounted on said glass opposite said guide member, a screw threaded stem for adjusting said abutment, and a compression spring between said abutment and said guide member.

4. In a door having a window in the upper portion thereof, a sliding glass closure for said window receivable in the lower portion of said door, a sloping door post on at least one side of said door having a guide groove therein, a sloping edge on said glass corresponding to the slope of said post, a tubular member mounted on the top of said glass, a guide member having a vertically elongated portion slidably received in said groove telescopically mounted in one end of said tubular member, an adjustable abutment in said tubular member opposite said guide member, a screw threaded stem in said tubular member for adjusting said abutment, and a compression spring within said tubular member between said guide member and said abutment.

Signed by me at South Bend, Indiana this
25 20th day of June, 1931.

PERRY W. SULLIVAN.
